(57) **CLAIM**

The ornamental design for a light assembly for an automobile, as shown described.

DESCRIPTION

FIG. 1 is a plan view of the light assembly and an air vent, showing my new design;

FIG. 2 is a left-side perspective view thereof; and,

FIG. 3 is a right-side view thereof.

The broken line showing of front end portion of a vehicle is included for the purpose of illustrating only and forms no part of the claimed design.
